UNITED STATES PATENT OFFICE.

SALVATORE SALTO, OF MILAN, ITALY.

LIMITER FOR ALTERNATING CURRENTS.

1,372,091.

Specification of Letters Patent. Patented Mar. 22, 1921.

Application filed February 15, 1919. Serial No. 277,235.

To all whom it may concern:

Be it known that I, SALVATORE SALTO, mechanical engineer, a subject of the King of Italy, and residing at Milan, Italy, whose post-office address is 7 Corso Vittorio Emanuele, Milan, Italy, have invented new and useful Improvements in the Limiters for Alternating Currents, of which the following is a specification.

10 The current limiting apparatus according to the present invention has, in comparison with known devices, the advantage that it interrupts the current only once when an overload occurs in the distribution system 15 and reestablishes the current automatically as soon as the overload is removed.

The accompanying drawing shows diagrammatically, by way of example, an apparatus constructed according to the present invention.

The current enters the apparatus at the terminal —1— from whence it passes to terminal —4—, flows through the winding of an electromagnet 17, passes to terminal 25 —5—, through fixed terminal —6—, spring —19—, terminal —7—, terminal —3—, thence passes to the distribution system, traverses the apparatus —8—9— inserted in the latter and finally returns to the other 30 terminal —2— of the apparatus. The circuit —1—4—5—6—7—3— is so designed as to offer a relatively small resistance.

From the point —1— branches off a conductor leading to the primary winding 11 of a 35 transformer —10—, and then to the point —3—, the resistance of the primary transformer winding being high relatively to the circuit —1—4—5—6—7—3—.

One end of the secondary winding —12— 40 of the transformer —10— is connected to the terminal —2— and the other to the end —13— of a second winding of the electromagnet —17—. The other end —14— of this winding is electrically connected to the 45 fulcrum —15— of the magnet armature —18—, which is preferably of large surface, and therethrough to the movable contact —16—, which does not contact with the spring —19— except when the armature 50 —18— is attracted by the electromagnet —17—.

The apparatus works as follows: When the main current flowing through the magnet coil —4—5— is in excess of the predetermined value, the armature —18— is attracted and, by means of contact —16—,

depresses the spring —19—, thus opening the contact between —6— and —19— and interrupting the main circuit. Owing to this interruption the current flows through the transformer primary winding —11—, the secondary 12 is energized and a current flows through —12—13—14—15—18—16—19—7—3—8—9—2—12—. The electromagnet —17— is now energized by the current flowing through the coil —13—14— and holds the armature —18— until the overload has been removed from the distribution system. On removal of the overload from the secondary or distribution system the current intensity decreases, the armature —18— is released, the spring —19— reestablishes contact with the point —16—, thus reestablishing the connection of the distribution system with the main system.

75

The most convenient transformation ratio can be selected so as to obtain the maximum variations in the current intensities for the resistance variations of the distribution system, which bring the load to the proximity of the maximum permissible load.

For adjusting purposes the apparatus is provided with a screw —20—, by means of which the armature —18— can be brought nearer to or away from the electromagnet —17—, and the electromagnet is provided with a slot —22— and an iron plate —21—, by means of which the resistance of the magnetic circuit of the magnet —17— can be varied in order to adjust the armature release.

The apparatus can be so adjusted that, when an overload occurs in the distribution circuit, the armature —18— is attracted and held up against the magnet poles until the overload is removed, so that no current can ever flow through the distribution system in excess of the current intensity allowed by the limiter.

The apparatus cuts off the current as soon as a short circuit takes place in the system, and restores it again automatically when the short circuit is removed; the apparatus accordingly works as a safety fuse.

The apparatus can also be used for the supply of electricity on the "forfeit" system for heating purposes, which advantage is not afforded by other limiters. A further advantage is that the apparatus works absolutely automatically, this permitting it to be put out of the reach of the user's hands.

In the construction of the apparatus it is not absolutely indispensable that the armature —18— be attracted by the main current magnetically.

5 Having fully described my invention, I claim, and desire to secure by Letters Patent:-

Limiter for alternating current comprising a main circuit, an electromagnet in said 10 circuit, an armature for said electromagnet acting as an interrupter for the main circuit, a transformer having its primary in parallel with the main circuit and its secondary in series with a winding on the elec- 15 tromagnet forming a circuit branched across

the line, the ratios of the coils being such that under normal conditions only a negligible current flows through the primary of the transformer, and when the main circuit is interrupted by the armature owing to an 20 excess of current passing therethrough, the current of the circuit of the secondary of the transformer energizes the electromagnet to hold open the main circuit, but the resistance of the primary winding diminishes the 25 current traversing the load circuit.

In testimony whereof I affix my signature this 22 day of January 1919.

SALVATORE SALTO.
